CLAMP

Carl F. Yandt, Minneapolis, Minn., assignor to Portable Structures, Inc., Minneapolis, Minn., a corporation of Minnesota

Filed Mar. 27, 1961, Ser. No. 64,499

Term of patent 3½ years

(Cl. D54—13)

FIG. 1.

FIG. 2.

FIG. 3.

FIG. 4.

FIG. 5.

FIG. 1 is a side elevational view of a clamp showing my new design;

FIG. 2 is an elevational view thereof taken from the right of FIG. 1;

FIG. 3 is an elevational view thereof taken from the left of FIG. 1;

FIG. 4 is a top plan view; and

FIG. 5 is a perspective view taken from the side opposite that shown in FIG. 1 and from the bottom thereof.

I claim:

The ornamental design for a clamp, as shown.
